UNITED STATES PATENT OFFICE.

WILLIAM C. GRAY, OF OAK PARK, ILLINOIS, ASSIGNOR, BY DIRECT AND MESNE ASSIGNMENTS, TO GRAY DOOR DRESSER COMPANY, OF CHICAGO, ILLINOIS, A CORPORATION OF ILLINOIS.

FOLDING DRESSING-TABLE AND THE LIKE.

1,245,582.

Specification of Letters Patent.

Patented Nov. 6, 1917.

Application filed July 24, 1916. Serial No. 110,827.

To all whom it may concern:

Be it known that I, WILLIAM C. GRAY, citizen of the United States, residing at Oak Park, in the county of Cook and State of

5 Illinois, have invented a certain new and useful Improvement in Folding Dressing-Tables and the like, of which the following is a full, clear, concise, and exact description.

10 My invention relates to improvements in dressing tables and the like.

The object of the invention is to provide a device of this character which may be folded compactly so as to occupy as little 15 space as possible when not in use, and one which may be mounted on a closet door if desired so as to be swung into the closet and concealed from view when the door is closed.

20 One embodiment of the invention is illustrated in the accompanying drawings, in which—

Figure 1 is a perspective view of the device;

25 Fig. 2 is a central sectional elevation thereof;

Fig. 3 is an enlarged side elevation of part of the dresser;

30 Fig. 4 is a section on the line 4—4 of Fig. 2;

Fig. 5 is a section on the line 5—5 of Fig. 2;

Fig. 6 is a section on the line 6—6 of Fig. 2;

35 Fig. 7 is a side elevation, partly in section, of the pivotal mounting for the drawers.

The dresser is mounted on a suitable supporting frame which comprises in the present case, upright wooden members 1—1, 40 which may be secured to the inside of a closet door 2, for example, although they may also be secured directly to a wall or other suitable support, if desired. At the top of said upright supports a rack 3 is 45 provided consisting of a horizontal shelf, supported on suitable side brackets 4 and arranged to hold bottles or other toilet articles. Beneath said rack, folding mirrors are arranged consisting of a large central 50 mirror 5 and two small side mirrors 6—6. These mirrors are supported preferably on suitable wooden strips 7 secured to the uprights 1—1. The mirror 5 is pivoted at 8 to said strips 7 and the side mirrors 6—6 are 55 secured thereto by hinges 9 whereby the

angle of the middle mirror may be adjusted and whereby said side mirrors may be folded in against the middle mirror, as shown in Fig. 5 for example.

Beneath the mirror 5, a suitable inclosure 60 10 is provided, which contains boxes or receptacles 11, 12, 13, shown pivoted at 13' which may contain pen and ink or other accessories necessary for writing, whereby the dresser may be used as a writing desk, if desired. The receptacle 13 which is suitable for pens, fits in the receptacle 12, as shown in section in Fig. 2. When these receptacles are pushed back into place, a compact arrangement is provided, as shown in said 70 figure.

A supporting cross piece 14 is secured to the uprights 1—1 and 7—7 as shown in Figs. 1 and 2, said cross piece being arranged to support the table or hinged leaf 15 provided with the hinges 16, as shown. Said table when in use is supported in horizontal position by folding arms 17 of any suitable type, which arms permit said table to be folded to vertical position as shown in Fig. 3 and 75 80 locked therein by a catch 18 of any suitable kind. It will be noted that the side mirrors are to be folded in against the middle mirror before the table is swung to vertical position and a very compact construction thereby results. Said table, being slightly wider than the supporting frame, including the wooden strips 7—7, hides the latter and the folding arms 17, when viewed from the front, 85 whereby a neat ornamental appearance is 90 attained.

Below the table 15 a pair of upright supporting members 19 are secured to the parts of the frame 1—1. A tray 20 is arranged at the upper end of said members beneath the 95 table. Horizontal frames 21, 22, 23 are secured to said members 19.

A vertical rod or bolt 24 is arranged at each side of the dresser passing through said horizontal members, as shown, and about 100 which bolt a plurality of swinging drawers, boxes or receptacles, 25, 26, 27 are arranged. Said receptacles are supported and guided in their movement by said frames. These receptacles or drawers are of uniform width 105 but may be of varying length or height, whereby they may be adapted to hold various different articles of wearing apparel. When the dresser is not in use, said receptacles are all swung to closed position and 110

project from the door or other support only a comparatively small distance. When the dresser is in use, they may be swung outwardly to a considerable angle, as illustrated in Fig. 6, thereby removing any obstruction from beneath the table and permitting convenient use of the latter. They may also be swung to different angles, whereby access to any one may be had without obstruction 10 from the one above it and without having to raise the hinged table.

As will be seen, the entire device may be very compactly folded whereby if it is desired to mount it on the inside of a closet 15 door, the latter may be readily swung open and shut without interference to its movement. Furthermore, the available size of the closet is not materially diminished when the door is shut. To use the dresser, the 20 door is simply swung back against the wall and the various parts of the dresser swung to the desired positions.

Although the device has been referred to 25 as a dresser or writing table, it is obvious that it is not limited to such use, as it may be otherwise employed. Also, all of the 30 features herein described need not be embodied in a single construction. Furthermore, various changes in the structural details and relative arrangement of parts may be made without departing from the spirit of the invention, as expressed in the appended claims.

What I claim as new and desire to secure 35 by Letters Patent of the United States is:

1. A folding device of the class described, comprising a suitable support, a plurality of folding mirrors secured thereto, a table hinged below said mirrors, and a plu-

rality of pivoted drawers mounted above 40 and below said table, said table being arranged to fold over said mirrors and the drawers pivoted thereabove, whereby a compact structure is provided.

2. A folding dressing table comprising a 45 plurality of uprights adapted to be secured to one face of a door, a mirror pivoted between said uprights, side mirrors pivoted to said uprights and adapted to fold over said first-mentioned mirror, a plurality of 50 horizontal swinging drawers pivotally mounted on said uprights below said mirrors, and a table hinged to said uprights and arranged to fold over said mirrors and certain of said drawers. 55

3. A folding dressing table comprising a plurality of uprights adapted to be secured to one face of a door, a mirror pivoted between said uprights, side mirrors pivoted to said uprights and adapted to fold over 60 said first-mentioned mirror, a plurality of swinging drawers pivotally mounted on said uprights below said mirrors, and a table hinged to said uprights and arranged to fold over said mirrors. 65

4. A folding dressing table comprising an upright support, a mirror secured to said support, side mirrors pivoted to said support and adapted to fold over said first mentioned mirror, a plurality of swinging 70 drawers pivotally mounted on said support below said mirrors, and a table hinged to said support and arranged to fold over said mirrors.

In witness whereof, I hereunto subscribe 75 my name this 20th day of July A. D., 1916.

WILLIAM C. GRAY.
